Filed Jan. 8, 1962, Ser. No. 164,884

10 Claims. (Cl. 81—9.1)

This invention relates to a novel seal crimping tool and in particular to a sealing tool for use with nonmetallic strapping materials.

Metallic strapping materials and metallic "seals" for fixing the ends of the strap together are well known in the packaging art. While metal strapping has many uses it also has many disadvantages. For example, metal does not easily go around right-angle corners of packages and therefore, when packages are standing, there is a point of maximum pressure applied to the metal strap at the edge. Furthermore, the metal used for metal strapping is relatively thin and therefore the edges are relatively sharp. If metal strapping suddenly is released from its seal or is broken during movement of the package, for example, it may strike a workman with considerable force thereby possibly causing serious bodily injury. Another disadvantage of metal strapping is that when it is removed from bound packages it is difficult to store it conveniently before disposal thereof or to salvage any of the scrap material.

Accordingly it has been proposed to utilize a strapping material made of synthetic plastic such as oriented fibrous polypropylene. This plastic material is melt-extruded, cooled, and thereafter stretched from between six to ten times its initial extruded length while being subjected to a temperature in the range between 250°—300° Fahrenheit. The stretching operation enables the strap to be applied under tension to the package to be bound without further stretching due to that tension. Thereafter, when the seal has been affixed the strap will not become loose. This plastic strapping material is capable of great flexibility so that it can go around the right-angle edges of packages with more compliance than metal strapping. Furthermore, unlike metal strapping it does not disfigure the container due to corrosion, nor does it present the same danger to workmen should the strapping become released during movement, for example.

Since this material is highly oriented and fibrous, it preferably should be "sealed" by appropriate seals and sealing techniques well-adapted to its particular characteristics.

In the prior art, the seal was usually a generally U-shaped metal device having a base and two parallel sides. The seal was placed around overlapping ends of the metal strapping after it had been tensioned by a special tool. When the sealing or crimping tool was placed around it and the jaws of the tool were closed, the sides of the seal were pressed inward toward one another flat against the strapping and, in addition, pressure was exerted by the crimping tool on the seal and strap in a direction transverse to the plane of the strapping. This transverse pressure caused deformation of the seal and the strap which it surrounded at certain points in a direction transverse to the plane of the strap. Sometimes this deformation actually resulted in flaps being cut into the seal and the enclosed metal strapping. These flaps which were angled downwardly, locked the metallic strap with the metallic seal to prevent slippage of the ends of the strap out of the seal. For metallic strapping materials this method was quite effective but for plastic strapping it is not well suited.

As stated above, plastic strapping material, especially highly-oriented fibrous materials such as polypropylene,

2

are made by stretching them after melt-extrusion. This stretching orients the molecules of the plastic material and prevents it from appreciable further stretching during the strap-tensioning operation so that the strap remains taut. Since the strapping material is relatively less strong in a direction transverse to its longitudinal axis than it is in the longitudinal direction, subjecting it to stresses or cutting flaps in it will cause the strapping material to disintegrate and to "shred" when the strapping material undergoes high tension. Thus, conventional seal-crimping devices cannot be successfully used with plastic strapping material to maintain the seals against the tensions usually employed with such strapping materials.

It is therefore an object of the invention to provide a novel seal-crimping device for use with non-metallic strapping materials.

Another object of the invention is to provide a novel crimping device for seals to be used to fasten plastic strapping materials together.

Yet another aim of the invention is to provide a novel seal crimping device for crimping seals to be used with fibrous plastic strapping materials.

Still other objects of the invention will be apparent to those skilled in the art from an examination of the specifications, claims, and drawings herein.

FIGURE 1 is a side elevation view of the novel crimping device with the handles in the maximum outward position.

FIGURE 2 is a side elevation view of my novel device with one of its cover plates removed to show its internal structure more clearly when the handles have been moved toward one another a considerable amount.

FIGURE 3 is a sectional view of the device taken along the section line 3—3 of FIGURE 2 in the direction of the arrows shown therein.

FIGURE 4 is a sectional view of the device taken along the section line 4—4 of FIGURE 2 in the direction of the arrows shown therein.

FIGURE 5 is a sectional view of the device taken along the section line 5—5 of FIGURE 2 in the direction of the arrows shown therein.

FIGURE 6 is a partial side elevation view of part of the jaws shown when the handles have been moved toward one another to the maximum inward position.

FIGURE 7 shows a before and after view of a seal processed by my novel crimping device.

These and other objects of the invention are accomplished according to my invention by providing a tool which produces a number of substantially identical corrugations in the seal and the material enclosed thereby, the corrugations being transverse to the longitudinal axis of the strap. The device comprises a pair of handles which, through intermediate linkage, are connected to two sets of opposed upper jaws. When the handles are closed the linkage causes the jaws to come down over the upper edges of the seal and to press the opposite sides of the seal toward one another and down over the overlapping strap ends. Further movement of the handles of the closed position causes means associated with the jaw linkage to move another set of jaws up against the back of the seal and to push the seal and the overlapping strap contained therein between the spaces between the upper jaws. By so doing, there are formed in the seal a series of transverse parallel corrugations, which are considerably deeper than deformations produced by conventional strapping devices. However, no cutting of the plastic strapping material occurs so that there is no weakening of the bond under the tensions required for taut binding of packages.

Upper jaw operation

As stated above, the crimping produced by my invention is done in a two-step operation although only one continuous movement of the handles is required to effect it. As seen in FIGS. 1, 2 and 3, there are two cylindrical handles 32a and 32b to which three rigid members 30a, 30b and 30c are attached as by bolts as shown in FIG. 1. The members 30a, 30b and 30c pivot about a pin or shaft 40 which is "spun on" in apertures in the outer plates 10 and 12 which are substantially parallel to one another and are generally shaped like a shield. Two other pins 21 and 23, arranged parallel to one another, are "spun on" in apertures in the plates 10 and 12. Also, two parallel pins 13a and 13b pass transversely through the plates 10 and 12 and have nuts screwed onto their ends as shown in FIGS. 1 and 3.

The member 30a has an aperture in its upper end through which pivot pin 35 extends and to which levers 28b and 28c are coupled. The members 30b and 30c have aligned apertures through which pins 33a and 33b pass and to which levers 28a and 28d are pivotally coupled. To each of the members 28a and 28b are coupled a pair of S-shaped members 26a and 17a, and to each of the levers 28b and 28c are coupled corresponding members 26b and 17b, by means of a vertically movable pivoting pin 31. The ends of pin 31 ride up and down within the opposed slots 8 and 9 in the plates 12 and 10 respectively in the manner to be explained below.

To the pair of members 17a and 26a are coupled three movable upper jaw members 14a, 14b and 14c by means of movable pivot pin 27. To the pair of members 17b and 26b are coupled, by means of a movable pin 29 which passes through them all, an opposing set of upper jaws 15a, 15b and 15c. It will be seen that when the upper jaws are in their open position as shown in FIG. 1, the pin 31 is toward the bottom of the slots 8 and 9 and the two sets of opposing upper jaws are so positioned that their lower active edges 16 do not touch the upper edges of the seal 18 shown in an end-on view.

Movement of the handles 32a and 32b toward one another causes the pins 33 and 35 to move toward one another and thereby causes the pair of linkage members 28a and 28d and the other pair of links 28b and 28c to move to a vertical position thereby forcing the pin 31 upward in the slots 9 and 8. By this construction a mechanical advantage of about 50:1 is obtained. Upward vertical motion of the pin 31, in turn, forces up the ends of the members 17a, 17b, 26a and 26b which are coupled thereto. The other ends of these latter members move outwardly in response thereby causing the jaw members 14a, 14b, 14c and 15a, 15b, 15c to pivot on their respective pivot pins 21 and 23 in opposing clockwise and counter-clockwise directions. As a result the jaw edges 16 come down on the sides 18a of the seal 18 forcing them to be folded over toward one another. FIGURE 2 shows the relative positions of the upper jaw sub-assembly elements when this action is completed. It should be noticed that at the end of this first inward movement of the handles 32a and 32b no corrugations have yet been made in the seal 18; only the sides have been folded over the enclosed overlapping ends of the plastic strap.

Lower jaw operation

Once the sides 18a of the seal 18 have been folded over, the jaw members 14a, 14b, 14c and 15a, 15b, 15c do not alter their position. Their active edges 16 serve to maintain the position of the seal 18 against further upward movement. However, as the handles 32a and 32b are pressed even further toward one another, it will be seen by reference to FIGS. 2 and 6 that the pin 31 engages the lower arcuate edge of rigid linkage member 24 whose upper end is sandwiched between two substantially identical and generally rectangular jaw members 20 and 22 having tapered upper edges similar to the lower edges 16 of the upper jaws. The lower edge of the

members 20 and 22 rest on pins 13a and 13b as shown in FIGS. 1 and 2. The pin 25 passes through all three members 20, 22 and 24. Two springs 11a and 11b are curled around the pin 25 and anchored at their ends to the fixed pins 13a and 13b. These springs tend to force the pin 25 downward and thereby tend to force the handles 32a and 32b apart when the crimping operation has been completed. On further inward movement of the handles 32a and 32b, the pin 31 forces the member 24 and the two jaw members 20 and 22 upward against the back of the seal 18 forcing parts of the seal and the straps contained therein upward in the spaces between adjacent ones of the upper jaw members 14a, 14b and 14c and 15a, 15b, 15c thereby producing a corrugated seal as shown in part B of FIG. 7. It will be noticed that the crimped seal has two humps in the upper direction and three humps in the lower direction. The seal may be of steel and have a length of 1 1/4 inches, for example. The peak-to-peak height of the seal may be on the order of 3/16"-1/4". It has been found that this number of corrugations with this depth in a seal of this length, when used with 1/2" polypropylene strap is quite satisfactory for most strapping operations.

The seal shown in FIG. 7 is known as a butt-type open seal but it should be understood that other seals such as the closed, overlapped-side type may also be used, if desired.

By constructing a crimping device in accordance with my teachings herein, a corrugated seal may be fastened about a plastic strap with a single inward movement of the handles. This construction permits the attainment of sufficient mechanical advantage for ordinary laborers to be able to produce deep corrugations in the seal with a device of competitive size and weight.

Other applications and modifications may occur to those skilled in the art from a perusal of the specification and drawings herein without departing from the essence of the invention. Consequently, I desire my invention to be limited only by the claims herein.

I claim:

1. Apparatus for fastening a seal about strapping material comprising:

first means including a first plurality of pivoting jaw members having spaces between them for folding the sides of said seal toward one another over said strapping material until they are substantially parallel to the back of said seal, said first means also including movable linkage means coupled to said jaws for transmitting motion thereto, and

second means including a second plurality of jaw members which are slidably positioned between the jaw members of the first plurality of pivoting jaw members for engagement by said linkage means and movable responsive to the movement of said linkage means beyond a predetermined point and constructed and arranged to exert pressure at predetermined points on the back of said seal to force said seal and its contents in the region of said points into the spaces between said first jaw members thereby to produce a plurality of corrugations in said seal and its contents.

2. The apparatus according to claim 1 wherein said first and second plurality of jaw members are parallel and have respective active edges adapted to be disposed substantially transverse to the longitudinal axis of said seal and wherein said corrugations are accordingly substantially transverse to said axis.

3. The apparatus according to claim 2 wherein said first plurality of jaw members includes two sets of oppositely-disposed jaw members and wherein said second plurality of jaw members includes one less jaw member than is in each of said sets of first jaw members.

4. Apparatus for fastening a seal about strapping material comprising:

a first plurality of pivoting jaw members having spaces between them,

- a plurality of handle members,
a plurality of interconnected rigid linkage members
coupled between said first plurality of jaw members
and said handle members, said linkage members
being constructed and arranged to cause said first
jaw members to press the sides of said seal inward
over said strapping material until they are substan-
tially parallel to the base of said seal when said
handles are moved toward one another a predeter-
mined distance. 5
- a second plurality of jaw members mounted in the
spaces between said first jaw members for free slid-
ing movement toward and in a direction normal to
the back of said seal, and
means directly moved by said linkage members when
said handles are moved toward one another more
than said predetermined distance for moving said
second jaw members in said direction until they
force parts of said seal and its contents into the
spaces between said first jaw members, thereby pro-
ducing a plurality of corrugations in said seal and
its contents. 15
5. The apparatus according to claim 4 wherein said
first plurality of pivoting jaw members includes two sets
of parallel opposing jaws,
wherein said plurality of linkage members includes
first and second pairs of links, each pair being con-
nected pivotally to one of said handle members,
and
third and fourth pairs of links pivotally connected to 30
said first and second pairs of links by a common
movable pivot pin passing through them all, each
of said third and fourth pairs of links being respec-
tively pivotally coupled to a different one of said
two sets of opposing jaws. 35
6. The apparatus according to claim 5
wherein each of said two sets of parallel opposing jaws
includes three jaw members,
wherein said second plurality of jaw members includes
two jaw members. 40
7. The apparatus according to claim 5
with the addition of two planar members disposed
parallel to one another and substantially enclosing
said first and second pluralities of jaw members, 45

- said planar members including apertures in which
pivoting means for said pivoting jaw members are
disposed and also including a plurality of slots in
which said common movable pivot pin is constrained
to move,
said planar members also including an aperture in
which means for pivoting said handles are disposed.
8. The apparatus according to claim 7 wherein said
planar members have oppositely disposed inset por-
tions between said first and second pluralities of jaw mem-
bers on which said seal may be set before said handles
are moved.
9. The apparatus according to claim 5
wherein said means for moving said second jaw mem-
bers in said given direction includes a rigid member
having one end sandwiched between said second jaw
members and coupled thereto by a pin,
said rigid member having an arcuate indentation in its
opposite end for engaging said common movable
pivot pin passes through said first, second, third and
fourth pairs of links.
10. The apparatus according to claim 9
wherein means are provided for biasing said pin which
is coupled to said rigid member and to said second
jaw members in a direction opposite said given di-
rection thereby tending to move said handles away
from one another.
